UNITED STATES PATENT OFFICE.

TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

SNAP SWITCH.

Application filed September 5, 1922. Serial No. 586,158.

This invention relates to electrical switches and particularly to switch mechanism of the snap action type and has for an object to provide a switch operating mechanism which is simple in construction, and comprises comparatively few parts. It is a further object of the invention to provide a switch mechanism which may be easily assembled and disassembled and which may be manufactured at a comparatively low cost.

It is a still further object of the invention to provide a switch mechanism which will be reliable in operation and not easily gotten out of order.

It is also an object of the invention to provide simple and effective means for indicating the position of the switch elements.

With these and other objects in view I have devised the mechanism illustrated in the accompanying drawing, in which

Fig. 1 is a top plan view of my switch showing a portion of the face plate in position, and the indicating means.

Fig. 2 is a side elevation of the switch mechanism shown in Fig. 1 the side wall of the insulating block being broken away, and the elements being shown in one extreme position.

Fig. 3 is a longitudinal sectional view through the switch mechanism of Figs. 1 and 2 showing the elements in the position they occupy immediately prior to the movement of the switch element.

Fig. 4 is a view similar to Fig. 2 showing a slightly different construction but looking from the other side of the switch mechanism.

Fig. 5 is a substantially central vertical transverse section through the switch mechanism of Fig. 4.

Fig. 6 is a top plan view of the rocker removed, and

Fig. 7 is a top plan view of a portion of the face plate of Fig. 4 showing the location of the indicating mechanism.

Referring to Figs. 1, 2 and 3, numeral 10 indicates a supporting block made of suitable insulating material and provided with a recess 11 in which the switch mechanism is mounted. Secured at opposite ends of the block are stationary contact elements 12 and 13 secured in the block by any suitable means such as screws 14, and electrically connected

with binding posts 15 adapted for connection with the lead wires, not shown. Extending across the open side of the block and secured thereto by any suitable means, as screws 16, is a supporting yoke 17 provided with threaded openings 18 to receive screws 19 for securing the face plate 20 over the switch mechanism. This face plate has an opening, 21 through which the lever 22 projects for operating the switch mechanism, presently to be described. The yoke also has transverse slots 23 to receive screws for attaching the same in the usual outlet box.

The yoke 17 is provided with spaced wings 24 arranged substantially parallel and extending into the recess in the block. The wings are substantially hooked shaped at their inner ends and are each provided with a curved notch 25 with inclined shoulders 26 and 27 extending from the opposite sides of these notches. A contact carrier 28, comprising a substantially flat bar or bridge piece of drawn stock, has one edge thereof in rocking engagement with the notches 25 with the other edge adapted to swing about this pivotal edge. The shoulders 26 and 27 are so arranged with respect to the notches 25 that when in extreme positions the contact carrier or bridge piece 28 will rest against the shoulders, and they will act as limit stops therefor, as shown in Fig. 2.

Also pivotally mounted on the wings 24 by any suitable means, as pin 29, is a rocker comprising parallel plates 30 each of which has at its inner end a recess 31 adapted to receive the reduced ends 32 of pin 33. This pin is embraced by a coiled spring 34 between the two plates 30, which has opposite free ends 35 adapted to extend through openings adjacent the ends of the oppositely extending arms of a resilient stirrup 36. This stirrup is substantially V-shaped in cross section as shown and adapted to engage at its apex the swinging edge of the contact carrier 28.

To either or both ends of the contact carrier 28 may be secured one or more switch elements 37 secured to a plate 38 preferably by suitable rivets 39, this head being preferably of insulating material and secured to the contact carrier by metal plate 40, the ends of the carrier being upset as shown at 41 over this plate. The switch element 37 is ar-

ranged to be moved into engagement with and from the stationary contacts 12 and 13 to close and open the circuit in the usual manner.

5 Secured to the rocker 30 is the operating handle or lever 22 so arranged that by swinging this lever the rocker will be swung about its pivot 29. This lever projects through an opening 42 in the yoke 17 and 10 also the opening 21 in the face plate 20, the openings 21 and 42 being in alignment. On opposite sides of the lever or handle 22 are substantially plane surfaces 43, arranged at an angle to the lever substantially the 15 same as the angle of the lever to the surface of the face plate when in its extreme position. These surfaces are also of such a size that when the rocker is in extreme positions it will move alternately into the opening 42 20 in the yoke 17 and beneath the opening 21 in the face plate. As this opening is smaller than these surfaces it will be closed thereby producing a neat appearance and effectively preventing entrance of dirt through 25 the opening in the face plate. Arranged on the plane surfaces 43 are indications 44, such as "On and Off", which are visible through the opening 21 in the face plate when the locker is in its extreme positions 30 and indicate the position of the switch element.

The operation is as follows:

In assembling, the rocker is pivoted by means of the pin 29 between the wings 24 35 of the yoke and the contact carrier 28 placed with one edge in the notches 25. The stirrup 36 is then placed over the swinging edge of the carrier, the free ends of the spring 34 inserted through the ends of the 40 stirrup, and the reduced ends of the pin 33 inserted in the recesses 31 of the rocker. As the spring is under tension this pin will be retained in these recesses by the action of the spring as will be obvious.

45 As the pin 33 is located eccentric to the pivot 29 swinging of the rocker on this pivot will swing the spring about the pivot, and also about the swinging edge of the contact carrier 28. Assuming the elements are 50 in one extreme position, as shown in Fig. 2 with the contact carrier resting against one of the inclined shoulders as 26, the movement of the lever upwardly to the dotted line position will swing the center of 55 the pin 33 through the center line 45 of the contact carrier. As it moves through this center line it will transfer the pull of the spring to the other side of the carrier and swing its free edge to the other extreme 60 position against the shoulder 27, swinging the switch element 37 with the carrier. As the center of the pin 33 is also eccentric to the notches 25, the movement thereof from the position shown in Fig. 2 to the center line 45 of the carrier will increase its

distance from the free edge thereof, and will thus wind the spring and place it under increased tension by drawing its free arms 35 toward the carrier. Immediately the center of the pin 33 passes through the center line 45 this spring tension will be exerted to swing the contact carrier to its other extreme position. Moving the lever 22 in the opposite direction will impart reverse movement to the elements and they 70 will operate in the same manner but in a reverse direction, to move the contact carrier and the switch element back to their original positions. Fig. 3 shows the position of the elements on this reverse movement just as the center of the pin 33 is passing 75 through the center line 45 of the carrier.

In Figs. 4 to 7 I have shown a slightly different arrangement of the indicating mechanism and the operating lever for the 80 rocker, the switch mechanism being, however, the same as that shown in Figs. 1, 2 and 3. In this construction the rocker 46 is substantially U-shaped having the parallel spaced legs 47 provided with the recesses 85 31 carrying the pin 33 and the spring 34, this rocker being pivoted on the wings 24 of the yoke 17 by the pivot pin 29 as in the first switch construction. The operating handle, however, is preferably a metal rod 90 48 having a knob 49 and is reduced at its inner end at 50 to provide a shoulder 51. This reduced inner end is riveted over to secure the handle to the cross bar 52 of the 95 rocker. The indicating mechanism comprises a plate 53 secured to the rocker and held thereagainst by the shoulder 51 the opposite ends of this plate extending at an angle to the lever as shown in Fig. 4 substantially equal to the angle of the lever to 100 the plane of the face plate 54 when in its extreme positions, so that when the lever is in its extreme positions the portion of this plate on the opposite sides of the lever will be positioned alternately in the opening 105 18 in the yoke and immediately under the opening 55 in the face plate to close the same. These positions of the plate 53 carry indications 56 to designate the positions of 110 the switch. The opening 54 in the face plate is preferably substantially the shape 115 as shown in Fig. 7 to allow for insertion of the knob 49 of the operation lever, and to present a neat appearance.

120 It will be apparent from the foregoing description that the switch mechanism is simple in construction and comprises comparatively few parts, and may be quickly and easily assembled and disassembled. As it is simple and comprises few parts, it will be of comparatively low cost to manufacture, will be reliable in operation and not easily gotten out of order. The indicating mechanism is also very effective and provides 125 closing means for the opening in the face 130

plate through which the operating lever extends and so will protect the switch mechanism from dirt, which would otherwise enter through this opening.

Having thus set forth the nature of my invention what I claim is:

1. In a device of the class described, a supporting yoke having wings provided with notches, a contact carrier comprising a flat bridge piece having an edge in rocking engagement with said notches, a pivoted rocker provided with recesses, an operating means connecting the carrier and rocker including a spring, and a pin support for said spring carried in the recesses in the rocker and held therein by said spring. 70
2. In a device of the class described, a support, a switch element pivoted in said support, a rocker pivoted in the support and provided with notches, a pin carried in said notches, a spring mounted upon and carried by said pin and connected with the switch element to operate the same, said spring arranged to hold the pin in said notches. 75
3. In a device of the character described, a support, a switch element pivoted in the support, a rocker pivoted in the support and provided with notches at one side thereof, a pin in said notches, a coil spring embracing said pin and provided with free ends having connection with the switch element to operate the same and said spring arranged to hold the pin in the notches. 80
4. In a device of the character described, a yoke having supporting wings provided with notches, a contact carrier comprising a flat bridge piece having one edge in rocking engagement with said notches, a rocker pivoted in said wings and provided with recesses at one side thereof, a pin in said recesses, a coil spring embracing said pin and provided with free ends, means connecting the free ends of the spring with the contact carrier to oscillate the same and arranged to draw the pin into the notches and hold it therein. 85
5. In a device of the character described, a yoke having supporting wings provided with notches, a contact carrier comprising a flat bridge piece having one edge in rocking engagement with said notches, a rocker pivoted in the said wings and provided with notches, a pin in the notches in the rocker, a coiled spring embracing said pin and having free arms, a stirrup extending over the other edge of the carrier and connected with said free arms, said spring and stirrup constituting operating means from the rocker to the carrier and also means to hold the pin in the said notches. 90
6. In a device of the character described, a yoke having supporting wings provided with notches, a contact carrier comprising a flat bridge piece having one edge in rocking engagement with said notches, a pivoted carrier having wings provided with notches, a pin in the notches in the carrier, a coil spring embracing said pin and having free arms, a stirrup extending over the other edge of the carrier and connected with said free arms, said spring and stirrup constituting operating means from the carrier to the yoke and also means to hold the pin in the said notches. 95
7. In a device of the character described, a support, a rocker pivoted in said support and provided with notches spaced from said pivot, a contact carrier mounted to oscillate in said support between the pivot and the notches, a pin carried in said notches, and operating means connecting said pin and carrier including a tension spring. 100
8. In a device of the character described, a yoke having supporting wings provided with notches, a rocker, a pivot for the rocker at the open sides of said notches, said rocker having notches located on the other side of the wing notches and opening away from the same, a contact carrier comprising a flat bridge member having one edge in rocking engagement with the wing notches, a pin carried by the rocker notches, and a spring carried by said pin and having operative connection with the other edge of said carrier. 105
9. In a device of the character described, a yoke having supporting wings provided with notches, a rocker, a pivot for the rocker at the open sides of said notches, said rocker having notches located on the other side of the wing notches and opening away from the same, a contact carrier comprising a flat bridge member having one edge in rocking engagement with the wing notches, a coiled spring embracing said pin and having oppositely projecting free ends, and a stirrup engaging the other edge of the contact carrier and provided with free ends connected to the free ends of the spring. 110
10. In a device of the character described, a support having an opening therein, a switch element, a rocker, a handle extending through said opening and connected to said rocker for operating same, a pin carried by said rocker, a spring embracing said pin and provided with free ends having connections with the switch element to oscillate the same when the rocker is moved to operating position. 115
11. In a device of the character described, a support having an opening therein, a switch element, a rocker, an operating means connecting the switch element and rocker including a spring with free ends supported on said rocker and connected to the switch element by a stirrup, and an operating handle attached to said rocker and extending 120
12. In a device of the character described, a support having an opening therein, a switch element, a rocker, an operating means connecting the switch element and rocker including a spring with free ends supported on said rocker and connected to the switch element by a stirrup, and an operating handle attached to said rocker and extending 125
13. In a device of the character described, a support having an opening therein, a switch element, a rocker, an operating means connecting the switch element and rocker including a spring with free ends supported on said rocker and connected to the switch element by a stirrup, and an operating handle attached to said rocker and extending 130

through the opening for operating the switch.

12. In a device of the character described, a support having an opening therein, a switch element, a rocker provided with an operating handle extending through said support, a pin carried by said rocker, a coil

spring embracing said pin and provided with free ends having connections with the switch element to operate the same when the rocker is moved to operating position. 10

In testimony whereof I affix my signature.

TONJES A. BOTH.
